UNITED STATES PATENT OFFICE.

JOHN A. OLSON, OF MINNEAPOLIS, MINNESOTA, ASSIGNOR OF ONE-HALF TO GUSTAF OLSON,
ONE-EIGHTH TO ETTA OLSON, AND ONE-EIGHTH TO PERRY D. SHERWIN.

ADJUSTABLE MAGAZINE-BINDER.

No. 875,947.

Specification of Letters Patent.

Patented Jan. 7, 1908.

Application filed April 4, 1907. Serial No. 366,360.

To all whom it may concern:

Be it known that I, JOHN A. OLSON, a citizen of the United States, residing at Minneapolis, in the county of Hennepin and State 5 of Minnesota, have invented certain new and useful Improvements in Adjustable Magazine-Binders; and I do hereby declare the following to be a full, clear, and exact description of the invention, such as will enable others skilled in the art to which it 10 pertains to make and use the same.

My invention has for its object to provide an improved detachable binder adapted for use to bind together periodicals, music 15 sheets, loose leaves and various other similar publications, and also adapted for use as a detachable cover for telephone books and the like.

To the above ends the invention consists 20 of the novel devices and combinations of devices hereinafter described and defined in the claims.

The invention is illustrated in the accompanying drawings, wherein like characters 25 indicate like parts throughout the several views.

Referring to the drawings, Figure 1 is a view partly in plan and partly in horizontal section, with some parts broken away, showing 30 my detachable binder applied to several magazines or the like. Fig. 2 is a view in elevation, showing the detachable binder, looking at the inner face thereof, some parts being broken away. Fig. 3 is a vertical section taken approximately on the line $x^3 x^3$ of Fig. 1. Fig. 4 is a view in edge elevation, showing the upper end portion of the so-called binding sheath of the device. Fig. 5 is a view in edge elevation, showing the 35 lower end portion of the binding sheath. Fig. 6 is a view in elevation, showing the upper lock plate of the device removed from working position. Fig. 7 is a view in elevation, showing the lower lock plate of the device removed from working position; and Fig. 8 is a view corresponding to Fig. 2, but 40 illustrating a somewhat modified construction of the device.

Referring first to the construction illustrated in Figs. 1 to 5 inclusive, the numeral 50 1 indicates the cover of the detachable binder, to the flexible intermediate portion of which is secured a flat but hollow thin metal sheath 2 that extends approximately 55 from top to bottom thereof. As shown in

Fig. 2, this sheath 2 is attached to the cover 1 by straps 3, but it will, of course, be understood that it may be thus secured by any suitable means.

At one edge of its upper end, the sheath 2 is provided with a longitudinally extended entrance slot 4, and at the opposite edge of its lower end, it is provided with a similar admission slot 5. A so-called lock plate 6 is adapted to be inserted into the upper end of the sheath 2, and a similar lock plate 7 is adapted to be inserted into the lower end of the said sheath. The lock plate 6 is provided with marginal flanges 8, 9 and 10. The flange 10 limits the downward or inward movement of the lock plate 6 and holds the flange 8 spaced from the end of said sheath while the flange 9 serves to close the entrance slot 4 when the said plate 6 is in working position, as shown in Figs. 2 and 3.

The lower lock plate 7 is provided with marginal flanges 11, 12 and 13. The short flange 13 limits the upper or inward movement of the lock plate 7 and holds the flange 11 spaced from the lower end of the sheath 2, and the flange 12 serves to close the entrance slot 5 when the said plate 7 is in working position, as shown in Figs. 2 and 3.

The numeral 14 indicates detachable binding rods, preferably of light spring steel wire, 85 the ends of which are bent laterally and then parallel with the bodies of the respective rods to form coupling fingers 15 that are adapted to be inserted into the ends of the sheath 2.

The loose leaves, pamphlets, books, magazines or similar articles indicated by the letter z are adapted to be held between the leaves of the cover 1 by the rods 14, which rods are placed between the leaves thereof close to the back or folded edges thereof, with the 90 ends 15 of the said rods projecting rearward thereof and engaged with the end of the sheath 2. When the lock plates 6 and 7 are applied as shown in Figs. 2 and 3, the entrance slots 4 and 5 of the sheath are closed 95 and the ends of the rods are interlocked with the sheath, but are, nevertheless, capable of lateral movements transversely of the sheath, so as to permit the articles z to assume their proper relative positions between the leaves 105 of the cover. The rods are adapted to be applied to the sheath or to be removed therefrom when the lock plates 6 are removed from the sheath by lateral movements of the fingers or ends 15 of the said rods through the 110

entrance slots 4 and 5. In fact, one end or finger of a rod may be inserted endwise into the sheath, and the other end thereof moved laterally through one or the other of the entrance slots 4 or 5. It is desirable to place the said slots 4 and 5 at opposite sides of the sheath so that a rod containing late number of the magazine may be applied to the right hand of the sheath, as viewed in Fig. 2, by first inserting its lower end into the end of the sheath and then moving the upper end thereof laterally through the slot 4; while the rod which holds the magazine of the oldest date may be removed from the left hand side of the sheath by moving its lower end 15 laterally outward through the slot 5 and then moving the upper end of the said rod endwise from said sheath. This manipulation, of course, adapts the device for the substitution of any other articles which happen to be applied to the rods.

Fig. 8 illustrates a simple form of the device which is especially adapted to hold but one rod 14^a. In this modified construction, 25 the sheath 2^a is narrower than the sheath 2, and in its lower end is shown as formed with a notch 2^b. A lock plate 6^a which, as shown, is provided with a downturned bifurcated outer end 6, is adapted to be inserted into 30 the upper end of the sheath 2^a. The sheath 2^a, at one side of its upper end, is provided with an entrance slot 2^c through which the hooked upper end of the rod 14^a may be passed laterally when the lock plate 6^a is removed and the lower hooked end of said rod 14^a is engaged in the notch 2^b in the lower end of the sheath. The device illustrated in 35 Fig. 8 is especially adapted for use to secure a book such as a telephone book, for instance, 40 to a suitable cover. The cover, however, is not shown in Fig. 8, but it will be understood that the sheath 2^a may be applied to the cover in the manner illustrated in Figs. 1 and 2 or by any other suitable means.

45 The device above described is of very small cost and has been found highly efficient for the purposes had in view.

What I claim is:

1. In a device of the kind described, the 50 combination with a sheath having open ends,

of one or more coupling rods having hooked ends engageable with the end of said sheath, and a lock device insertible into one of the ends of said sheath and serving to hold the said rod or rods interlocked with said sheath, substantially as described.

2. In a device of the kind described, the combination with a sheath having open ends, and a longitudinally extended entrance slot, of one or more rods having hooked ends engageable with the ends of said sheath, and a lock plate insertible into one end of said sheath and arranged to close the longitudinal entrance slot thereof, substantially as described.

3. In a device of the kind described, the combination with a sheath having open ends, and entrance slots extending longitudinally from the two ends thereof but at the opposite edges of said sheath, and a multiplicity of 70 rods having hooked ends engageable with the ends of said sheath and adapted to be passed laterally through the entrance slots thereof, and lock devices insertible into the ends of said sheath and arranged to close the longitudinal entrance slots thereof and thereby hold the rods interlocked with said sheath with freedom for lateral adjustments, substantially as described.

4. In a device of the kind described, the combination with a flat metallic sheath 2 having open ends and longitudinal slots 4 and 5 extending from its open ends at the opposite edges of said sheath, coupling rods 14 having hooked ends 15 engageable with 80 the open ends of said sheath and movable laterally through said entrance slots, and lock plates 6 and 7 insertible into the ends of said sheath and having, respectively, stop flanges 8—9 and 11—12, which flanges 9 and 90 12, respectively, are adapted to close said entrance slots 4 and 5, substantially as described.

In testimony whereof I affix my signature in presence of two witnesses.

JOHN A. OLSON.
